Atty.

UNITED STATES PATENT OFFICE.

SAMUEL M. COFFMAN, OF KANSAS CITY, MISSOURI, ASSIGNOR TO THE BARBERS ELECTRIC SPECIALTY COMPANY, A CORPORATION OF KANSAS.

VIBRATORY MASSAGING DEVICE.

1,391,759.

Specification of Letters Patent. Patented Sept. 27, 1921.

Application filed February 19, 1918. Serial No. 218,170.

To all whom it may concern:

Be it known that I, SAMUEL M. COFFMAN, a citizen of the United States, residing at Kansas City, in the county of Jackson and State of Missouri, have invented certain new and useful Improvements in Vibratory Massaging Devices, of which the following is a specification.

This invention relates to improvements in massaging devices, and the objects of the invention are to produce a device of this character which is simple in construction, economical to manufacture and maintain, and which is not likely to get out of order.

Another object is to produce a massaging device in which different forms of applicators can be used, any one of which may be removed or replaced in a few moments.

Another object is to provide means by which the speed of the device may be easily and quickly regulated.

In order that said invention may be fully understood, reference will now be made to the accompanying drawing, in which:

Figure 1 is a vertical section of the device.

Fig. 2 is a plan view of the device.

Fig. 3 is a plan view of the device, with the top plate removed.

Fig. 4 is a cross section, taken on line IV-IV of Fig. 1, showing a member for controlling the speed of the device when desired.

Fig. 5 is a side elevation of a different form of applicator, from that disclosed by Fig. 1.

In carrying out the invention, I employ a tubular handle 1, provided with fixed bearings 2 and 3, respectively, at each end, in which a shaft 4 is journaled. Said shaft 4 is provided at one end with a collar 5 to prevent it from moving longitudinally in the bearings 2 and 3. An eccentric 6 is fixedly mounted upon one end of said shaft 4, for a purpose which will hereinafter appear. The opposite end of the shaft 4 is provided with an elongated slot 7 and a socket 8, for the reception of a flexible shaft adapted to be rotated by a motor (not shown) the end of the shaft being beveled as disclosed by Fig. 1, to guide the end of the shaft into said slot 7 and the socket 8.

The tubular handle 1 is provided at one end with a housing 17, carrying a pivot 9 therein, having a nut 10 threaded upon its

lower portion to secure it in place in the 55 housing 8.

An oscillatory lever 11 is fulcrumed upon said pivot 9. The inner end 12 of said lever is bifurcated to straddle the eccentric 6, by means of which it is oscillated. The outer 60 end of said lever 11 is provided with an internally threaded tubular extension 15, adapted to receive corresponding threads upon the different forms of applicators.

A cover plate 16 is provided for the housing 17, to exclude dust and other foreign matter therefrom. Said plate 16 is held in place by a screw 17^a threaded into a tubular recess in the pivot 9.

18 designates a brake for retarding the 70 speed of the device. Said brake 18 consists of a cylindrical member having a perforation 19 therein, through which the shaft 4 extends. The ends 20 of the brake project through oppositely-disposed holes 21 in the 75 tubular handle 1, thus allowing it to be operated from either side by pressing thereon with the thumb until the desired speed is obtained.

23 designates one form of applicator, 80 consisting of a hollow, bell-shaped member, provided at its rear end with a tubular threaded extension 24 adapted to engage the threads in the tubular extension 15 of the lever 11.

In operation, the shaft 4 is rotated by a 85 flexible shaft attached to a motor (not shown). The rotation of the shaft 4 causes the eccentric 6 to rotate, which in turn oscillates the lever 11, thus rapidly oscillating the applicator and producing the desired 90 massaging effect.

The modified form of applicator, disclosed by Fig. 5, consists of a plate 28, having a plurality of cone-shaped projections 29, adapted to produce the massaging action. 95 The rear side of the plate 28 is provided with a threaded extension 30 by means of which it is secured to the lever 11, in the same manner as the applicator 23.

Having thus described my invention, what 100 I claim and desire to secure by Letters Patent, is:

1. A massaging device consisting of a handle, a shaft journaled in said handle, a brake projecting through said handle and engaging the shaft so that the speed thereof can be retarded by pressure on said brake, 105 an applicator, and means associated with one

end of the handle and driven by the shaft to actuate said applicator.

2. A massaging device consisting of a handle, a shaft journaled in said handle, a brake having an opening through which said shaft freely extends, said brake projecting through opposite sides of the handle so that pressure on either end will retard the shaft, an applicator, and means associated with

one end of the handle and driven by the shaft to actuate said applicator.

In testimony whereof I affix my signature, in the presence of two witnesses.

SAMUEL M. COFFMAN.
